UNITED STATES PATENT OFFICE

ERNEST L. BYFIELD, OF CHICAGO, ILLINOIS, ASSIGNOR TO COLLEGE INN FOOD PRODUCTS COMPANY, OF CHICAGO, ILLINOIS, A CORPORATION OF ILLINOIS

DESIGN FOR A DISPENSING CONTAINER

Application filed October 21, 1932. Serial No. 45,438. Term of patent 3½ years.

To all whom it may concern:

Be it known that I, ERNEST L. BYFIELD, a citizen of the United States, residing at Chicago, in the county of Cook and State of Illinois, have invented a new, original, and ornamental Design for a Dispensing Container, of which the following is a specification, reference being had to the accompanying drawing, forming a part thereof, in which Figures 1 and 2 are side and top plan views, respectively, of a dispensing container, showing my new design.

I claim:

The ornamental design for a dispensing container, as shown.

In testimony whereof I affix my signature.

ERNEST L. BYFIELD.
